(57) **CLAIM**

The ornamental design for a magnetic nail sweeper, as shown and described.

DESCRIPTION

FIG. 1 is a fragmented perspective view of the magnetic nail sweeper made in accordance with the present invention; FIG. 2 is a front elevation view thereof; FIG. 3 is a fragmented side elevation view thereof; and, FIG. 4 is a rear elevation view thereof.

The broken lines are for illustrative purposes only and form no part of the claimed design.
